(57) **CLAIM**

What is claimed is the ornamental design for a floorboard relocation kit, as shown and described.

DESCRIPTION

FIG. 1 is a perspective view of my new design for a floorboard relocation kit, showing the right side bracket and the right side engine guard bracket;

FIG. 2 is a perspective view of the floorboard relocation kit, showing the left side bracket and the left side engine bracket;

FIG. 3 is a front elevational view of the left side bracket;

FIG. 4 is a rear elevational view of FIG. 3;

FIG. 5 is left side elevational view of FIG. 3;

FIG. 6 is a right side elevational view of FIG. 3;

FIG. 7 is a top plan view of FIG. 3;

FIG. 8 is a bottom plan view of FIG. 3;

FIG. 9 is a front elevational view of the ride side bracket;

FIG. 10 is a rear elevational view of FIG. 9;

FIG. 11 is a left side elevational view of FIG. 9;

FIG. 12 is a right side elevational view of FIG. 9;

FIG. 13 is a top plan view of FIG. 9;

FIG. 14 is a bottom plan view of FIG. 9;

FIG. 15 is a perspective view of the left side engine guard bracket of the floorboard relocation kit;

FIG. 16 is a left side elevational view of FIG. 15;

FIG. 17 is a right side elevational view of FIG. 15;

FIG. 18 is a top plan view of FIG. 15;

FIG. 19 is a bottom plan view of FIG. 15;

FIG. 20 is a front elevational view of FIG. 15; and,

FIG. 21 is a rear elevational view of FIG. 15.

The right side engine guard bracket of the floorboard relocation kit is a mirror image of the left side engine guard bracket. The broken lines showing a motorcycle in FIGS. 1 and 2 are included for the purpose of illustrating the components of the floorboard relocation kit in position of use, and form no part of the claimed design.
